PAGE 2

FIG. 3

FIG. 4

FIG. 5

FIG. 1 is a front perspective view of a casing for a calculator or the like embodying my new design.

FIG. 2 is a right side elevational view thereof.

FIG. 3 is a top plan view.

FIG. 4 is a front view; and

FIG. 5 is a rear view.

The left side view of the cover case is a mirror image of the right side view as shown in FIG. 2.

The broken line disclosure of the calculator keys are shown for illustrative purposes only to show the environment in which the cover case is used.

I claim:

The ornamental design for a casing for a calculator or the like, as shown and described.
